UNITED STATES PATENT OFFICE.

ROBERT GORTON, OF NEWTON, MASSACHUSETTS.

CLASP FOR HOSE-SUPPORTERS.

1,109,583.

Specification of Letters Patent. Patented Sept. 1, 1914.

Application filed November 8, 1911. Serial No. 659,173.

To all whom it may concern:

Be it known that I, ROBERT GORTON, a citizen of the United States, residing in Newton, in the county of Middlesex and 5 State of Massachusetts, have invented certain new and useful Improvements in Clasps for Hose-Supporters, of which the following is a specification.

My invention relates to clasps for hose-10 supporters of the kind in which a button of soft rubber secured to a metallic base plate by a rivet forming a central support is associated with a loop usually made of metal and having an opening through which a portion 15 of the upper part of the stocking is forced by the button and which is of sufficient size at its upper end to receive the fabric and button, while its lower end is narrower than the button head being wide enough only to 20 receive the button shank and the intervening fabric which latter is thus clamped against the opposing sides of the shank by the inner side walls of the loop. Hose-sup-25 porter clasps of this general description have been extensively used since the issue of my Patent No. 552,470 of December 31, 1895, but such clasps have heretofore commonly been made with round buttons, i. e., buttons 30 with heads circular in cross section and having shanks of similar form, and have been secured to the base plate by an ordinary rivet forming a central support.

In the use of hose-supporter clasps of the kind referred to a portion of the fabric at 35 the upper part of the stocking is made to pass through the loop and over the button and is pressed by the opposite side walls of the narrow part of the loop against the sides of the button shank, the pressure thus ex-40 ereted being depended on mainly to firmly clamp the fabric in the clasp. Where the shank of the button is circular in cross section it is obvious that the area of the parts thereof which lie close to the side walls of 45 the loop is somewhat limited so that the pressure of the loop against the shank is localized and the fabric is clamped at two points. This is especially true where the 50 flanged head of the button extends all the way around, for when such a button is put under strain it moves upwardly in the loop sufficiently to release any pressure on the fabric at the bottom of the loop. The pressure at the side walls of a round shank is 55 sufficient to prevent the garment from slip-

ping, but it has been found that under strain the stocking is liable to begin tearing at these points because of the localized bite of the button and loop.

I have found that superior results are obtained by using an oblong button, i. e., a button having a shank whose major axis, which lies parallel with the major axis of the loop, is considerably longer than its minor axis. In this way an extended bearing surface is afforded on the shank against which the fabric is pressed by the loop and possibility of tearing is greatly reduced. Moreover the head of the button is so shaped that the button will not move upwardly in 70 the loop under strain, and will in fact exert a pressure against the end of the loop as well as the sides. This button I secure to the base plate in any suitable way but preferably in the manner shown in my Patent 75 No. 1,057,396 of Mar. 25, 1913.

Other features of my improvements will be hereinafter described.

In the accompanying drawings, Figure 1 shows a front elevation of a hose-supporter 80 clasp embodying my invention connected with suspending webbing in the usual way. Fig. 2 is a perspective view of the same. Fig. 3 is a perspective view of a novel form of loop associated with webbing and an 85 oblong button. Fig. 4 is a perspective view of the button with parts broken away.

The loop member A of the clasp, shown in Figs. 1 and 2, is of well known construction and is attached to webbing in the usual way. 90 The button C is attached by means of any suitable device to a base plate E which is connected with the webbing in the ordinary manner.

The button proper C, is made of soft rubber or similar material which is elastic, somewhat compressible and of such nature as to provide antislipping surfaces. Preferably the whole of the part C is made of such material, but inasmuch as the shank is the 100 most active part of the button, the shank only may be thus made, while the head of the button may have other characteristics. The shank of the button, as shown, is oblong presenting straight flat surfaces c on opposite sides which lie in use close to and parallel with the opposite side walls of the narrow part of the loop opening and are supported and backed by the flat sides of the 105 post. The head of the button is formed by 110

side flanges c' , there being no end flanges, the ends of the head being substantially in line with the ends of the shank.

By using an oblong button the shank of the button is given extended straight bearing surfaces coöperating with the sides of the loop, the button is provided with an efficient support and by forming the head of the button with flanges at the sides only the button, when under strain, will remain well down in the loop.

The improved button may be used in connection with the usual form of loop shown in Figs. 1 and 2, but I prefer to use a loop like that shown in Fig. 3 in which the upper part is bent or extended forwardly beyond the plane of the lower part, thus producing a recess a at the rear and a bulge or hump a' in the front disposed forwardly of the vertical plane of the lower or narrow part of the loop. The bending of the loop is produced at the wider part of the loop opening, the upper or wider part of the opening being bounded by the bent side walls a^2 of the loop. This construction has many advantages, it facilitates in connecting the loop with the button and also in separating it therefrom: it ensures the locating of the side walls of the lower part of the loop below the head or top flange of the button before the loop is drawn up enabling the button to pass down to the end of the loop and causing the loop to engage the button shank throughout the entire extent of the side walls thereof: it largely prevents chafing of that part of the stocking which covers the button, as garments of the wearer will come in contact with the hump or bulge of the loop and be held away from the button; and it provides a space to receive a bunch of the stocking should one be formed at the upper edge thereof when connecting the clasp with the hose.

I claim as my invention:

1. A hose supporter clasp comprising a loop having an opening wide at one end and relatively narrow at the other where the side

walls of the opening are made approximately straight and parallel, and a button having an oblong shank substantially equal in width 50 to the width of the narrow portion of the loop opening and having approximately straight, parallel side walls of a length sufficient to engage the said straight, parallel side walls of the loop throughout their 55 length, and side flanges on the button forming a head therefor and terminating short of that end of the shank nearest the outer extremity of the narrow portion of the loop whereby the button when in use and under 60 strain will remain deep in the loop and present the full length of the side walls of the shank to the opposing walls of the loop opening, and the loop may draw the fabric to which the clasp is attached into firm contact with the outer end of the button shank.

2. A hose-supporter clasp, comprising an oblong button having an oblong shank and a head formed by side flanges and a loop formed with a straight, relatively narrow, 70 flat lower part for engaging the button shank and which is parallel with the button flanges, and a wide button-receiving upper part which is bent to form a hump disposed in front of and wholly above the button-engaging part of the loop.

3. A hose-supporter clasp, comprising webbing, a base plate attached thereto, an oblong button having an oblong shank attached to the base plate and a loop formed 80 with a relatively narrow, straight, flat lower part for engaging the button shank which is parallel with and close to the base plate, and a wide button-receiving upper part, the sides of which upper part are bent to form a 85 forwardly extending hump containing the wider part of the loop opening.

In testimony whereof, I have hereunto subscribed my name.

ROBERT GORTON.
